UNITED STATES PATENT OFFICE.

SOMMERFIELD E. MILLER, OF CHICAGO, ILLINOIS.

TOILET CASE.

Application filed November 5, 1923. Serial No. 672,960.

To all whom it may concern:

Be it known that I, SOMMERFIELD E. MILLER, a citizen of the United States, and a resident of the city of Chicago, county of Cook, and State of Illinois, have invented certain new and useful Improvements in Toilet Cases, of which the following is a specification.

My invention relates to improvements in 10 toilet cases, commonly known as "vanity cases", the object of the invention being to provide a simple and convenient construction of this character capable of a wide variety of uses.

15 Other objects will appear hereinafter.

The invention consists in the combinations and arrangements of parts herein- 20 after described and claimed.

The invention will be best understood by 25 reference to the accompanying drawings forming a part of this specification, and in which,

Fig. 1 is a front view of a construction 30 embodying the invention;

Fig. 2 is an enlarged similar view of the 35 same showing the construction in opened condition;

Fig. 3 is an enlarged detail view illustrating 40 a battery mounting employed in the construction;

Fig. 4 is a section taken on line 4—4 of 45 Fig. 2;

Fig. 5 is a section taken on line 5—5 of 50 Fig. 2; and

Fig. 6 is a diagrammatic view illustrating 55 the electric circuit employed in the construction.

The preferred form of construction as 60 illustrated in the drawings comprises a suitable hollow body 7 in box-like form and having a hinged lid or closure 8. The lid 8 is provided with the usual mirror 9 and boxes or containers 10, 11 and 12 are removably mounted on a swinging partition 45 13 in the body 7, said parts constituting the usual and common parts of an ordinary toilet case commonly known as a vanity case. The body 7 and lid 8 are provided with suitable handles 14 and suitable lock 50 15. These parts in themselves constitute no part of my present invention, except in so far as they cooperate with the parts to be presently described.

An electric light bulb 16 is mounted on 55 the partition 13 and connected in circuit with two upstanding slip contacts 17 as

shown, a switch 18 being also included in 60 said circuit. The slip contact 17 consists of two adjacent metallic spring leaves adapted to frictionally receive and engage the usual terminals 19 of an electric battery 20 and the electrical connections are such, as indicated, to supply current to said light from said battery when the switch 18 is closed.

The battery 20 is held in place by means of a flexible folder 21 adapted and arranged to be folded about said battery and secured in place by means of a snap fastener 22. A light opening 23 is provided in the lid 8 70 opposite the light 16 and a glass lens 24 is secured in said opening and whereby light will be emitted through said lens from said electric light 16 when the lid 8 is closed, the arrangement being such as to then 75 bring the light 16 directly behind or opposite the lens 24.

By this arrangement a toilet case is provided having an electric light which may be utilized either to illuminate the interior 80 of the case and the mirror 9 when the case is opened, or also used as a flash light when the case is closed. The specific form and arrangement of parts disclosed is a simple and effective one for the purpose.

While I have illustrated and described the preferred form of construction for carrying my invention into effect, this is capable of variation and modification without departing from the spirit of the invention. 90 I, therefore do not wish to be limited to the precise details of construction set forth, but desire to avail myself of such variations and modifications as come within the scope 95 of the appended claims.

Having described my invention what I claim as new and desire to secure by Letters Patent, is:

1. A construction of the class described 100 comprising an openable enclosure having provision in one wall for the passage of light from the interior; an electric light in said enclosure set opposite said provision and arranged to illuminate the interior thereof when opened and to emit light through said provision when the enclosure is closed; a circuit and switch for operating said light; a battery connected in said circuit; and a folder detachably embracing said battery, substantially as described.

2. A construction of the class described 110 comprising a hollow body having a hinged

- closure, there being an opening through said closure, and a lens in said opening; an electric light in said body arranged opposite said lens when the closure is closed; 6 an electric circuit including said light and two slip battery contacts; a flexible folder arranged to embrace a battery having terminals engaging said slip contacts; a detachable fastening for said folder arranged 10 to hold the same in position embracing said battery; and a switch in said circuit, substantially as described.
3. A toilet case comprising a two-part casing; there being a window in one part; 15 a lamp in the other part in position to come behind said window; an electric circuit for
- said lamp including slip contacts; a battery having terminals engaging said slip contacts; a flexible folder arranged to embrace said battery and slip contacts; a detachable 20 fastener combined with said folder and arranged to hold the same in position embracing said battery; and a switch in said circuit, substantially as described.
- In testimony whereof I have signed my 25 name to this specification in the presence of two subscribing witnesses.

SOMMERFIELD E. MILLER.
